UNITED STATES PATENT OFFICE.

LESLIE ARNETT, OF PROPHETSTOWN, ILLINOIS.

DRINKING FOUNTAIN.

Application filed February 4, 1924. Serial No. 690,558.

To all whom it may concern:

Be it known that LESLIE ARNETT, a citizen of the United States, residing at Prophetstown, in the county of Whiteside 5 and State of Illinois, has invented certain new and useful Improvements in Drinking Fountains, of which the following is a specification.

This invention relates to new and useful 10 improvements in drinking fountains and pertains particularly to that class which is especially adapted for use in enabling stock or poultry to have access thereto at all times without requiring any manual labor in filling 15 the fountain and keeping the same supplied with a sufficient quantity of water.

One of the important objects of the present invention is to provide a drinking fountain of the above mentioned character, 20 wherein means is associated therewith for permitting the water which is supplied from a suitable source to the drinking fountain to be heated during the cold weather, thus preventing the freezing of the water in the 25 drinking fountain and rendering the device ready for use at all times and insuring a sufficient quantity of drinking water regardless of the condition of the weather.

Another important object of the invention 30 is to provide a drinking fountain of the above mentioned character, wherein means is associated therewith for regulating the supply of water from a suitable source to the fountain which will be entirely automatic in 35 its operation and will not require the attention of a person in order to actuate the same.

A still further object is to provide a 40 drinking fountain of the above mentioned character, wherein the parts are so arranged as to enable the same to be readily assembled or disassembled whenever necessary in a minimum amount of time and without having to use any complicated tools or the like.

45 A further object is to provide a drinking fountain which is inexpensive, strong and durable and further well adapted for the purposes for which it is designed.

50 Other objects and advantages of the invention will become apparent during the course of the following description.

In the accompanying drawings forming a part of this specification in which like numerals designate like parts throughout the same,—

55

Figure 1 is a front elevation of my drinking fountain.

Figure 2 is a plan view thereof.

60

Figure 3 is a sectional view taken on line 3—3 of Fig. 1.

Figure 4 is a section taken on line 4—4 of Fig. 1.

65

Figure 5 is a section taken on line 5—5 of Fig. 4.

Figure 6 is a section taken on line 6—6 of Fig. 5.

70

Figure 7 is a section taken on line 7—7 of Fig. 6.

Figure 8 is a side elevation of the supply pipe and coil.

75

Figure 9 is a section taken on line 9—9 of Fig. 3.

Figures 10 and 11 are detail views of the coil housing or casing.

In the drawings wherein for the purpose of illustration is shown the preferred embodiment of my invention, the numeral 1 designates a supply tank or receptacle which is adapted to contain the water to be supplied to the drinking fountain to be herein-

80

after more fully described. Adapted to be associated with the supply tank 1 is the casing designated generally by the numeral 2 and the latter is substantially rectangular in

85

design, as more clearly illustrated in Fig. 2 of the drawings. The casing as well as the supply tank are preferably constructed of galvanized sheet metal, although it is to be understood that any other material may be

used as seen fit. Extending vertically adjacent one of the ends 3 of the casing is the partition 4. Any suitable means is provided for holding the same in proper position within the casing and in proper spaced relation with respect to the end 3 thereof. The

90

partition extends down into the casing to a point above the bottom thereof so as to provide an air space between the bottom of the casing and the lower edge of the partition.

Extending transversely across the top of the casing adjacent the intermediate portion thereof is a supporting strip 5. This sup-

95

porting strip 5 is adapted to support the

100

bottom of the supply tank 1. The supply tank 1 is supported by the supporting strip 5 and the bottom of the supply tank 1 rests on the bottom of the casing.

porting strip has its ends bent inwardly and secured to the opposite sides of the casting in any suitable manner, as is clearly illustrated in the drawings. The purpose of this strip is to provide a means for supporting one of the sides of the drinking trough designated by the numeral 6.

This drinking fountain or trough comprises a substantially shallow rectangular 10 designed receptacle and has all of its sides with the exception of one tapering downwardly. The straight side of the drinking fountain is adapted to be arranged adjacent the heating stove hereinafter more fully described for the purposes also to be herein-after more fully described. The upper edges of the drinking fountain 6 are provided with the flanges 7 whereby a means is provided for enabling the drinking fountain to be supported on the casing 2 in such a manner as to have the flanges of the drinking trough extending over the end portion of the casing, the front and rear sides thereof and the supporting strip 5.

It will be understood that the drinking fountain will rest on the upper edges of the casing and will be supported in one of the corners thereof. By providing the vertical partition 4 heretofore described, it will be seen that substantially two compartments are formed in the casing, one of the compartments preferably the one adjacent the end 3 being smaller than the other. The drinking fountain is supported in one end 35 of the larger compartment while an oil stove or the like, such as is shown at 8 in the drawings, is supported in the opposite end of the same compartment. The smaller compartment is adapted to support therein the fuel 40 supply tank 9, which has communication by means of a suitable pipe 10 extending through the air passage and along the bottom of the casing with the oil stove, whereby the fuel will be supplied to the stove and preferably to the wick thereof, so as to permit the stove to properly operate. Any character of stove may be used in connection with my invention and I do not wish to confine myself to any particular kind of stove. In the present instance I have shown 45 an oil stove as used in conjunction with my invention and the purpose thereof will be presently described. The casing 2 is further provided with a hinged cover 11 and this cover is of such length and construction as to only extend over the oil stove and the end compartment containing the fuel supplying tank 9, and a portion of the trough as is clearly illustrated in the drawings. For the 50 purpose of permitting the proper supply of air to the oil stove, I provide in the end 3 of the casing 2 an opening and housing 12 therefor. The opening has a screen, positioned thereover to prevent the entrance of

any foreign substance therethrough and the 65 cover 12 will thus permit a sufficient quantity of air to be admitted to the end compartment containing the fuel supplying tank, and to the other compartment wherein the stove is supported, thus permitting the stove 70 to burn.

This casing 2 is arranged substantially in front of the supply tank 1 and has communication therewith by means of the flanged coupling 13 and the conduit 14, 75 which extends from the coupling into the central portion of the casing and preferably is arranged above the oil stove 8. Supported within the supply tank 1 is a suitable housing 15 which also has communication with 80 the conduit 14 and the flanged coupling 13 associated therewith by means of the conduit 16, and this housing is adapted to also support therein the lower end of the chimney 23.

A supply pipe 17 has its intermediate 85 portion coiled as shown at 18 in the drawings, and is adapted to extend through the conduits 14 and 16, respectively, in such a manner as to have the coiled portion 18 thereof extending beyond the outer end of 90 the conduit 14 and directly above the burner of the oil stove 8. The inlet end 19 of the supply pipe 17 is threaded into an opening provided in the bottom of the conduit 16 and is adapted to communicate with the interior 95 of the supply tank 1 for permitting the water contained therein to pass into the inlet end of the supply pipe and through the coiled portion thereof and for the purpose of permitting the water from the supply 100 tank to be supplied to the drinking fountain 6 supported in the larger compartment of the casing, I have provided a coupling 20 in the supply pipe 17 adjacent the coiled portion thereof, and a discharge or outlet pipe 105 21 is associated therewith and communicates with the supply pipe so as to enable the water passing therethrough to be discharged through the discharge or outlet pipe 21 into the bottom or side of the drinking fountain 110 in order to fill the latter. The outlet end 19' of the supply pipe 17 is also threaded into an opening provided in the top of the conduit 16 directly above the inlet end of the supply 115 pipe and is also adapted to communicate with the interior of the supply tank 1.

The purpose of having the coiled portion 18 of the pipe 17 extending directly above the burner of the oil stove 8, is to permit the heat from the stove to heat the water 120 contained in the coiled portion of the supply pipe and consequently result in the circulation of the water therethrough whereby the water contained in the supply tank 1 will be kept warm and will be prevented 125 from freezing during the cold weather. A suitable hood such as is shown at 22 in the drawings, extends over the coiled portion 18

of the supply pipe and the oil stove for preventing the waste of any heat and the smoke from the stove will pass through the conduits and the housing 15 and will be discharged through a suitable chimney or the like such as is shown at 23 in the drawings, the discharge end of which is disposed above the top of the supply tank. The hood 22 is supported in position over the oil stove and around the coiled portion 18 of the supply pipe by means of the sleeve 25 which is secured on the inner free end of the conduit 14 and the sleeve being provided with the flanged portions 26 for engagement with the flanged portions 27 formed on the hood 22.

In order to assure the proper filling of the drinking trough or fountain 6 and to prevent overflow thereof, I provide the float valve mechanism shown at 24 in the drawings, and as the same is of the well known construction, it is not thought necessary to go into detail relative to the same, it being sufficient to state that the purpose thereof is to close the opening in the trough whereby the latter is filled when a sufficient quantity of water has been discharged into the trough, and as the water is consumed by the stock or poultry, the float will descend and consequently cause the valve to again be automatically raised and permit the further supply of water from the supply tank 1 through the supply pipe 17 to the drinking trough, thus assuring the continuous and automatic supply of a sufficient quantity of water within the drinking fountain as long as there is a sufficient quantity of water within the supply tank. In Figure 4 of the drawings it will be seen that the hinged cover 11 has the end flange portion 11' thereof extending down into the drinking trough 6 so as to cover the float valve mechanism 24 against access thereto by the stock.

Of course, it will be understood that during the warm weather the burner or oil stove will not be used and that the water will be supplied from the supply tank to the drinking fountain in the manner as above described. However, during the cold weather it has been experienced that the drinking fountains now used in conjunction with the supply of water to fowl or stock, that the water will freeze and hence, prevent the stock or fowl from obtaining any water. To overcome this, I have provided the stove 8 in such a manner as to permit the continuous circulation of warm water through the device and thus prevent the freezing of the water in the drinking fountain during the cold and freezing weather. The stove is located adjacent the drinking trough 6 and as the latter has its sides tapering heat from the stove will come in direct contact with the trough and tend to heat the same. The housing 15 will also cause the heat passing therethrough to keep the water in the supply

tank 1 warm and as heretofore described the warm water circulating through the pipe 17 will be discharged through the outlet end 19' of the pipe 17 into the supply tank.

If desired, a water jacket of any conventional construction may be used in place of the coiled portion 18 of the supply pipe 17, whereby the water passing therethrough will be more readily heated by the stove 8.

The simplicity of my device enables the same to be easily and readily assembled and will not require any attention when once placed in use. It first is to be understood that there is a sufficient quantity of water in the supply tank 1 and a sufficient quantity of fuel in the fuel supply tank 9 whereby the operation of the device will be maintained for an indefinite length of time without requiring any attention.

Furthermore the parts are so arranged as to enable a person to have ready access thereto without having to completely disassemble the device and prevent the operation thereof.

From the foregoing description of the construction of my improved apparatus, it will be seen that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having thus described my invention, what I claim is:—

1. In combination with a supply tank; of a casing, a drinking trough removably supported in said casing, a conduit connecting said tank with said casing, a water supply pipe extending through said conduit, the inlet end of said supply pipe being disposed in said supply tank, said supply pipe having a coiled portion provided therein extending beyond the opposite end of said conduit, a heater mounted in said casing directly below said coiled portion of said supply pipe, a discharge pipe extending from said water supply pipe into said drinking trough, and a valve in said trough for regulating the supply of water thereto.

2. In combination with a supply tank; of a casing, a drinking trough removably supported in said casing, a conduit connecting said tank with said casing, a water supply pipe extending through said conduit, said supply pipe provided intermediate of its ends with a coiled portion extending beyond the end of said conduit, a heater mounted in said casing directly below said coiled portion of the supply pipe, a discharge pipe continuing from the coiled portion of said supply pipe, and extending into said drinking trough, the ends of said supply and dis-

charge pipes being threaded and terminating in elbows bent in opposite directions, registering openings in the top and bottom of said conduit aligning with the inlet and outlet of said elbows, threaded extensions connected with said elbows and projecting through the registering openings in said

conduit, and nuts engaged with the threaded ends of said last mentioned threaded extensions to retain the inlet and outlet ends 10 in proper position with respect to the conduit, as and for the purposes described.

In testimony whereof I affix my signature,
LESLIE ARNETT,
